Application October 29, 1951, Serial No. 17,160

(Cl. D44—15)

To all whom it may concern:

Be it known, that I, Jack Bloch, a citizen of the United States, residing at Leominster, Worcester County, and State of Massachusetts, have invented a new, original, and ornamental Design for a Bowl or the like, of which the following is a specification, reference being had to the accompanying drawings, forming part thereof, in which:

Figure 1 is a top plan view of a bowl or the like, showing my new design;

Fig. 2 is a side elevational view thereof, and Fig. 3 is a vertical section taken on the line 3—3 of Fig. 1.

The dominant feature of the design resides in the floral ornamentation which consists of a representation of a woven or open-work basket containing long-stemmed flowers with some of

the flowers drooping over the sides of the basket, the flowers being arranged in an over-all substantially circular pattern, as shown.

I claim:

The ornamental design for a bowl or the like, substantially as shown and described.

JACK BLOCH.
